UNITED STATES PATENT OFFICE.

BENJAMIN WOLHAUPTER, OF NEW ROCHELLE, NEW YORK, ASSIGNEE TO THE RAIL JOINT COMPANY, OF NEW YORK, N. Y., A CORPORATION OF NEW YORK.

PROCESS OF MAKING RAIL-JOINT BARS.

1,083,579.

Specification of Letters Patent.

Patented Jan. 6, 1914.

Application filed August 15, 1912. Serial No. 715,246.

To all whom it may concern:

Be it known that I, BENJAMIN WOLHAUPTER, a citizen of the United States, residing at New Rochelle, in the county of 5 Westchester and State of New York, have invented certain new and useful Improvements in Processes of Making Rail-Joint Bars, of which the following is a specification.

10 This invention relates to an improved process of manufacturing rail joint bars of the continuous type, that is of the type having a main angle-bar splice member fitting the fishing spaces and flanges of the rails, 15 and a base section formed integral with said splice member and constituting a rail seat and support.

The main object of the invention is to provide a simple and practical method of manufacturing these joint bars, whereby they can be produced rapidly, accurately, and economically without complication, and by the use of any suitable mechanical appliances or instrumentalities that may be available for, 25 or adapted to, the purpose.

A special object of the invention is to provide a process which possesses certain practical advantages over processes that are now in use for making rail joint bars of the continuous type, and which also provides for the development of the bar into such form as to leave, within the bar, a well defined clearance for the rail flange, not only at and beyond the extreme outer edge thereof, but 35 also above the upper outer portion of the rail base flange, thereby contributing materially to the flexibility and resiliency of the joint bars about the rail flanges so that the same will readily adjust and adapt itself to and 40 upon the rail flanges.

While including a novel series of manipulations to secure the special rail-flange-clearance above referred to, the present invention also distinguishes quite radically from the 45 known processes of making rail joint bars, of the continuous type, in the feature of first rolling the bar with the rail-supporting base section at right angles to the perpendicular plane of the splice member, or substantially parallel to, but at a distance from, 50 its required final rail-seating position, thus leaving a large and spacious rail flange-receiving recess that is of greater depth vertically than the thickness of the rail flange. 55 This particular section admits of the desir-

able and advantageous use of a heavy and substantial tongue in the rolls, and also permits shear knives to be employed for shearing the bar clean at the end. Thereafter, preferably while cold, the rail-supporting 60 base member is pressed to its final rail-seating position, and this same pressing step is also utilized to deform the foot flange portion of the joint bar in such manner as to secure an ample and well defined top-clearance for the rail flange above the upper portion thereof at, and adjacent to, its outer edge, as well as beyond its outer edge. This 65 pressing of the rail-supporting base member to its final position takes care of any inequalities in the foot portion of the bar from rolling. It will thus be noted that the new process, according to the present invention, 70 does not require sawing and the special punches and grinding apparatus as employed in other processes. It supplies a method which shears the ends of the bar in a very clean and economical manner, and at the same time provides, in the first pressing, 75 for the taking care of any inequalities produced by roll wear.

While various instrumentalities may be utilized in carrying out this invention and various alterations made in the precise manner of handling the bar during the course 80 of its development without departing from the invention, one of the ways in which the process may be carried out in a practical manner is suggested in the accompanying 85 drawings, in which—

Figure 1 is a sectional elevation of a pair of rolls of a rolling mill, illustrating the roll pass for giving the bar its final reduction and shape, and showing the bar, in section, 90 within the pass. Fig. 2 is a perspective view illustrating the step of cutting the rolled bar into rail joint lengths by means of shears. Fig. 3 is a perspective view illustrating the step of pressing or upsetting the 95 whole lower portion of the bar to bring the base section to a rail seating position, and also to force the foot flange of the bar upwardly to provide the top clearance space for the rail flange at and above the outer edge portion thereof. Fig. 4 is a detail view 100 of the joint bar having its final form as imparted thereto by the pressing step. Fig. 5 is a side elevation of a rail joint embodying 105 joint bars of the design produced by the present process, the view showing one of the 110

joint bars removed to expose the continuous and uniform rail seat and support. Fig. 6 is a sectional view of the said rail joint including the modified continuous bars as made by the process claimed herein, and showing by full and dotted lines, respectively, the movement to which the whole lower portion of the joint bar, below the upright splice member thereof, is subjected to bring the base section or plate to a rail seating position and to force the foot flange of the bar upwardly to provide lateral and top clearance for the rail flange.

Like references designate corresponding parts in the several figures of the drawings.

The billet or bar blank is first subjected to the action of a series of roll passes of known form, which deliver from the final set of passes a bar having a pronounced change in the conventional section, such change being a much greater vertical depth of the rail flange receiving recess. That is to say, the series of roll passes secures the progressive distribution and reduction of the metal, and the gradual shaping of the bar, until it reaches a form substantially that of its final shape, but possessing in this form, no seat or support for the rails. The rolled form of the bar referred to is shown in section in Fig. 1 of the drawings, and it will be seen therefrom that the bar has been rolled with its base member in a position wherein it is disposed in a position parallel to, but at a distance from, its required final position. At this stage of the process the bar includes the main angle-bar splice section or member *a* having an inclined foot flange *b*, the toe member or spiking foot *c*, a base member or section *d* which is rolled at substantially right angles to the perpendicular plane of the splice member *a*, and the rail flange-receiving recess *e*, between said base section and the inclined foot flange of the bar, the said recess *e* being of considerably greater depth vertically than the thickness of the rail flange. Accordingly, it will be observed that below the foot flange *b*, the joint bar is formed with a bottom portion that includes the rail seating member *d*, and may also include a toe member or spiking foot *c*.

In explanation of the rolling step that produces the design and cross section of the bar shown in Fig. 1 of the drawings, it will be observed that a pair of finishing rolls, designated A and B respectively, are designed and constructed to provide between them a pass P corresponding in shape to the general cross sectional appearance of a rail joint bar of the continuous type, but modified to the extent of having a large and substantial tongue *t* to the roll A which gives final area to the large and spacious rail flange-receiving recess *e* of the rolled bar. The next step in the process is to cut the rolled bar into rail joint lengths. This is

accomplished by a shearing operation which leaves the ends of the bar free from fins and burs, so that no further finishing operation thereon is required or necessary. Any suitable shearing means may be employed for carrying out the shearing step of the process, as for instance by suitably operated shearing knife members 1 and 2 having cutting edges conforming to the cross sectional contour of the rolled bar. As shown in Fig. 2 the knife member 2 may constitute the ledger blade, and the knife member 1 the movable blade. The rail flange recess *e* being large, a large and strong knife tongue *e'* can be made in the shear blade 2 which will not be liable to break when being operated.

After the shearing of the bar into rail joint lengths, the joint bar is subjected to a final shaping pressure to bring the base section to a rail seating position, and to define the rail flange clearance above mentioned. This may be accomplished in various ways, but for illustrative purposes one method is suggested in Fig. 3 of the drawings. In this figure of the drawings, the rolled bar is shown as being placed in a die press which includes an anvil-base 3 having a movable clamping member 4, and a vertically movable presser head 5 operating above both the anvil-base and the said clamping member. These parts are so constructed and arranged as to admit of a bodily movement of the entire lower portion of the joint bar below the junction of the foot flange *b* with the upright splice member *a*, whereby the base section *d* may be pressed into a rail seating or rail engaging position and the foot flange *b* deformed to provide a top clearance for the rail flange above the outer portion thereof. That is to say, in utilizing an apparatus of the kind shown in Fig. 3 to accomplish these results, the anvil-base 3 may be provided at the upper side thereof with a die groove or depression 6, the bottom of which underlies and is spaced a material or appreciable distance below, both the foot flange *b* and the toe member or spiking foot *c* of the joint bar when the latter is placed in the press. Also when the joint bar length is first placed in the press and clamped therein, as shown in Fig. 3 of the drawings, the base section *d* thereof occupies a parallel spaced relation with reference to the upper side of the clamping member 4, said upper side of the clamping member being flat and straight throughout. Likewise, the under side of the presser head 5 is flat and straight throughout, so that when the latter is forced downwardly upon the bottom of the joint bar, held as shown in Fig. 3, the entire lower portion of said joint bar, as above referred to, is moved downwardly with the result of moving the foot flange *b* and also the toe member *c* into the die groove 6, thus causing

a deforming of the foot flange *b* of the bar. This deformation assumes the character of a bulge or bow which gives to the interior rail flange-receiving recess *e* such form as to 5 provide a well defined clearance for the rail flange, not only at and wholly beyond the outer edge thereof, but also a top clearance above the upper outer edge portion of the said flange. This clearance bulge or bow *f* 10 as produced in the press shown in Fig. 3, or equivalent apparatus, is plainly shown in Fig. 4 of the drawings.

In the pressing step above described, no 15 change or alteration in the structural form or shape of the base section *d* of the bar is involved, but the whole of this base section is pressed into a rail base engaging position throughout the full length of the bar, thus giving a continuous rail seat or bearing for 20 the bases of the rails from end to end of the joint, as plainly illustrated in Figs. 5 and 6 of the drawings. In other words, as far as the base section of the bar is concerned, the pressing or equivalent step provides for 25 shifting this base section from its rolled position, viz., parallel to but spaced a distance from its operative or final working plane, viz., into a rail base engaging position throughout the length thereof.

30 I claim:

1. The process of making rail joint bars which consists in subjecting a bar blank to a roll pass to produce an angle-bar splice section having a foot flange, a rail-seating base 35 member and a toe member, with the base member and toe member disposed in a position parallel to but at a distance from their required final positions, and subsequently forcing the base member and toe member 40 into their required final positions.

2. The process of making rail joint bars which consists in subjecting a bar blank to a roll pass to produce an angle bar splice section having a foot flange, and a bottom 45 portion including a rail seating member, with the said rail seating member disposed in a position parallel to, but at a distance from, its required final position, and subse-

quently displacing said bottom portion to bring the rail seating member into its said 50 final position and to also thereby deform the foot flange by displacing the same to its final position.

3. The process of making rail joint bars which consists in subjecting a bar blank to 55 a roll pass to produce an angle-bar splice section having a foot flange, a rail-seating base member and a toe member, with the base member and toe member disposed in a position parallel to but at a distance from their required final positions, and subsequently forcing the base member and the toe member into their required final positions, and thereby deforming the foot flange by displacing it in an upward direction at the 60 outer end thereof.

4. The process of making rail joint bars which consists in subjecting a bar blank to a roll pass to produce an angle-bar splice section having a bottom portion including a 70 rail-seating base member disposed in a position parallel to but at a distance from its required final position, then shearing the rolled bar to lengths, and finally displacing the entire bottom portion of the joint bar to 75 bring said portion to its final required position.

5. The process of making rail joint bars which consists in subjecting a bar blank to a roll pass to produce an angle-bar splice section having a foot flange and a bottom portion including a rail-seating base member 80 disposed in a position parallel to but at a distance from its final required position, and finally displacing the entire bottom portion 85 of the joint bar to bring such portion to final finished position, and thereby simultaneously deforming the foot flange by displacing it in an upward direction.

In testimony whereof I hereunto affix my 90 signature in the presence of two witnesses.

BENJAMIN WOLHAUPTER.
